UNITED STATES PATENT OFFICE.

JOSIAH F. FRENCH, OF PHILADELPHIA, PENNSYLVANIA.

BUCKSAW.

SPECIFICATION forming part of Letters Patent No. 375,061, dated December 20, 1887.

Application filed March 8, 1887. Serial No. 230,157. (No model.)

To all whom it may concern:

Be it known that I, JOSIAH F. FRENCH, of the city and county of Philadelphia, State of Pennsylvania, have invented a new and useful Improvement in Bucksaws, of which the following is a true and exact description, reference being had to the drawings which accompany and form a part of this specification, and wherein—

10 Figure 1 represents a bucksaw embodying my invention, and Figs. 2 and 3 represent side views of the blade thereof.

Similar letters of reference indicate similar parts in the several views.

15 The bucksaw is composed of a saw-blade, A, having teeth *a*, the teeth of the said saw-blade being cut in such a manner or upon such a surface that their crowns form a concave curve. By this means when the center tooth 20 bites the article to be sawed the other teeth lying within the line of the said tooth will also bite the article to a greater depth, proportioned to the distance which they project beyond the horizontal line drawn through the 25 center tooth. It will thus be seen that the power which is to a greater or less extent lost at the end of the inward and outward throw of the ordinary bucksaw is, by means of my

invention, fully utilized. The outside edge of the saw-blade being in the form of a convex 30 curve, as indicated, I am enabled to have the teeth lie in the desired concave line without weakening the blade.

My improved saw is provided with the saw-frame B and the tightening device C, the blade 35 being united to the frame by suitable rivets or retaining-pins, D D. In the saw as thus constructed the line of strain in tightening the frame will be that represented by a line joining the rivets D D, and will therefore be very 40 close to the teeth, and consequently holding the blade at its point of greatest strain with great rigidity.

Having thus described my invention, what I claim, and desire to secure by Letters Patent, 45 is—

A bucksaw consisting of a frame, B, a tightening device, C, and a saw-blade, A, the teeth of which lie in a concave curve and the back in a convex curve, said blade being connected with the frame by rivets or pins D, located in a line near the saw-teeth.

JOSIAH F. FRENCH.
